DUST GUARD PLUG LOCKING MEANS

William H. Sale, Sandston, Va., assignor, by
mesne assignments, to Central Railway Supply
Company, Chicago, Ill., a corporation of
Illinois

Application November 29, 1937, Serial No. 177,041

3 Claims. (Cl. 286—6)

My invention relates to devices adapted for use with present day types of journal boxes of railroad cars and constitutes means whereby the closure plugs for the dust guard pockets will be locked in place against removal; said means, however, being such that removal of the plugs, for access to the dust guards, may readily be accomplished when desired.

The objects and advantages of my invention will be readily comprehended from the following detailed description of the accompanying drawings wherein:

Figure 1 is a longitudinal sectional view of a journal box with the journal, wedge block, the brass and dust guards in side elevation and illustrates one form of my improved locking means applied to the guard plug; the means and plug being in section.

Figure 2 is an enlarged sectional view of the dust guard receiving end of the journal box and of my improved means; the section being taken in a different vertical plane.

Figure 3 is a sectional view of the upper portion of the dust guard receiving end of a journal box with portions of the dust guards and plug in place and illustrates another method of applying the type of locking means employed in the preceding figures.

Figure 4 is a perspective view of the locking means employed in Figures 1, 2 and 3 and illustrates the form of the device before its application to the journal box.

Figure 5 is a cross sectional view of a journal box and journal illustrating a modification of my locking means and the different method of application.

Figure 6 is a perspective view of the locking means employed in Figure 5.

Figure 7 is a perspective view of another modified form of my plug locking means.

Figure 8 is a sectional view of the dust guard pocket or inner end of a journal box with dust guards and plug inserted in place and illustrates the method of application of the modified means shown in Figure 7.

Figure 9 is an elevation of the wheel side of the journal box and of my locking means illustrated in Figure 7.

In railroad car journal boxes at present in use, the inner end of the journal box 15 is open to permit the insertion of the journal 16 therethrough and this inner end of the journal box is usually provided with a pocket, as at 17, adapted to receive suitable dust guards illustrated at 18. These dust guards generally consist of thin sheets

or plates provided with a cut out or opening to fit onto the journal as shown in Figure 1 and adapted to close the opening 19 about the journal against the ingress of cinders and dirt. After the dust guards 18 have been put into place 5 through the open top of the pocket 17 and the journal inserted therethrough, the upper end of the pocket 17 is then closed by a suitable key or plug 20 generally composed of wood and slightly tapered toward bottom to permit the plug to 10 be driven into place; the plug being of length commensurate with the length of the pocket extending transversely of the journal box. The plugs 20 are intended to prevent ingress of cinders, dirt and the like through the top of the 15 pocket.

During operation of the cars, the constant jars and vibration cause the plugs 20 frequently to be forced upwardly and out of the top of the pocket, allowing the undesirable ingress of cinders and dirt into the journal box. 20

My invention has for its object the provision of means of an inexpensive nature and of comparative simple construction which will permit easy application thereof to the journal boxes and 25 the plugs at the upper ends of the dust guard receiving pockets.

My improved means, as exemplified in Figures 1, 2 and 3, consists of a sheet metal plate 21 shown in perspective in Figure 4, of thickness just sufficient to have the necessary strength and at the same time enable the body portion of the plate to extend vertically in the upper end of the guard pocket intermediate of the closure plug 20 and a wall of the journal box. The plate is of length 35 somewhat greater than the vertical width of the walls at the inner end of the journal box at the dust guard receiving pocket. The plate 21 is provided at one end with a pair of vertical slits thereby to provide the two side tongues 23, 23 and 40 the intermediate tongue 24. The lower end of plate 21 is shown somewhat tapered or reduced into the depending portion 25 and this depending portion bent laterally with the distal end 26 thence curved or bent upwardly as shown in Figure 45.

The device 21 as previously stated is made of bendable sheet metal which permits the tongues 23, 23 and 24 to be bent laterally after the locking means has been inserted into the plug receiving end of the dust guard pocket of the journal box; the device being inserted before the plug is driven into place. 50

In Figures 1 and 2 I show the method of application of my improved locking means employed in 55

cases where the means has been inserted in the plug receiving end of the dust guard pocket before the journal box 15 has been mounted on the journal which enables the device to be inserted through the inner or journal introducing opening 19. Where the application is thus made to the journal box, the upstanding distal end or lip 26 is then disposed to the outside of the journal box, namely intermediate of the inner end of 10 the journal box and the hub of the wheel (indicated at 27); the tongues 23 preferably are then bent laterally across the top of the plug 20 while the tongue 24 is bent laterally across the top of the outer wall 28 of the journal box and thence 15 downwardly along the outer side thereof as indicated in Figures 1 and 2.

It is apparent from the construction shown that the laterally disposed portion of the lower end 25 with its upstanding lip 26 and the laterally and downwardly bent tongue 24 will prevent any vertical movement or displacement of the locking means while the laterally disposed tongues 23, 23 will finally lock the plug 20 against upward travel or removal and hence ensure a constant closure for the upper end of the dust guard receiving pocket being maintained.

Where the application of my improved locking means is intended for journal boxes of cars in use, the improved locking means must be inserted through the front end of the box provided with the usual lid or closure 29, see Figure 1. To permit such application, the journal box 15 must be jacked up, the wedge block 30 and brass 31 then removed thus providing sufficient space 35 above the journal 16 to permit introduction of my locking plate 21 therethrough. In situations of this kind the locking means 21 is inserted upwardly through the plug receiving pocket, with the lower tapered end portion 25, 26 arranged 40 within the journal box as shown in Figure 3 and the laterally disposed portion 25 arranged beneath the shoulders of wall 32 of the journal box. In order to lock the plate in place, certain of the 45 tongues, for example the side tongues 23, are bent laterally across the top of wall 32 of the journal box and thence downwardly against the outer side of the wall 32, thereby firmly holding the locking means in place against movement. The plug 20 is then driven into the upper end of 50 the guard receiving pocket, and the other tongue 24 is then bent laterally across the top of the plug 20 toward the inner end of the journal box, as shown in Figure 3, thereby firmly locking the plug 20 against any upward movement.

55 In Figure 5 I illustrate another form of my locking means, namely a type which may be easily applied to the journal boxes without need of jacking up the latter. This type of locking means in its initial form is shown in perspective in Figure 6 in the form of a substantially right angularly bent plate 33 consisting of the upper leg or side 34 and the depending side or leg 35. The upper leg 34 has a partially severed portion which is bent downwardly to provide the depending tongue 36; while the lower end of the depending side or leg 35 is curled or slightly bent in what may be termed an inward direction as shown at 37.

As this type of locking means is intended to 70 be applied at the ends of the plug 20, a pair are employed as shown in Figure 5 and they may be applied after the dust guard plug 20 has been inserted in place by forcing the tongue 36 downwardly between the end of the plug and the side wall of the journal box; the device being of sheet

metal possessing sufficient resiliency to permit it to slightly flex and be sprung about the shoulder or rim of the journal box while the tongue is being inserted. After the tongue 36 has been completely driven into place, the upper side or leg 34 will lie flush with the top of the plug 20, while the curled or bent edge 37 on the depending or vertical side 35 will snap or extend beneath the rim 38 of the journal box wall. A similar locking device is preferably also applied to the opposite side wall of the journal box, namely at the other end of the plug 20; and in order to ensure against any improper removal of the devices it is preferred to tack weld the curled edges 37 to the side walls of the journal box as indicated at 38 in Figure 5.

In Figure 7 I disclose another modification of the device. The device 39 is made of sheet metal having a sufficient amount of resiliency to enable the device to be flexed or sprung into place. The locking means shown in Figures 7 to 9 consists of a preshaped element with an upper portion 40, and a depending portion 41, integrally united by the intermediate outwardly bowed or looped portion 42 which enables the required flexing action between the upper portion 40 and the depending portion 41 without undue strain and which also causes the portions 40 and 41 to more or less spring or snap toward each other when the device assumes its final position on a journal box. 30

The upper side 40 has a partially severed portion which is bent downward to provide the tongue 43 which is intended to be disposed in the plug receiving opening in the journal box as shown in Figure 8 where the tongue 43 is driven between the plug 20 and the rear wall 28 at the top of the journal box, while the main part of side 40 overlaps the plug.

The lower marginal edge of the depending side 41 is bent or curled inwardly, namely toward the 40 side of the device on which top 40 is located, as shown at 44. This curled edge 44 is intended to engage beneath the inner or rear wall 28 of the journal box after the upper part of the device has been positioned and applied as shown 45 in Figure 8. The resiliency provided by the upwardly disposed loop 42 permits leg or depending portion 41 with its incurled edge 44 to flex outwardly while the tongue 43 is being driven into place and as soon as the upper part 40 is flush with the top of the plug the curled edge 44 will then be adjacent the lower edge of the journal box wall 28 and will snap therebeneath, thereby firmly locking the device in place.

With the forms of the device illustrated in Figures 4 and 7, merely one need be employed for each journal box, as these locking devices are preferably located intermediate of the sides of the journal box and hence intermediate of the ends of the plug 20.

It will be understood, of course, that while the tongues 23, 23, 24 of the device shown in Figure 4 are intended to be bent down into place as shown in Figures 1, 2 and 3, the device is made with sufficient rigidity to resist the upward pressure of the plug 20 encountered during car operation.

The various exemplifications illustrated in the drawings and described in the specification are 70 believed to be the best embodiments of the invention in connection with car journal boxes as at present employed, but certain modifications are possible and may be made without, however, departing from the spirit of my invention.

What I claim is:—

1. Dust guard plug locking means comprising a metallic plate adapted to be inserted in the upper end of the dust guard pocket of a railroad car journal box to extend parallel with a vertical wall of the pocket, the lower end of the plate being bent laterally into hook form and disposed through the journal receiving opening in one of the dust guard pocket walls and adapted to effect holding engagement with said wall, while the upper end of the plate is provided with bendable portions adapted to be bent laterally in opposite directions with one portion overlapping the upper edge of one wall of the dust guard pocket and adapted, in conjunction with the lower hook end, to lock the plate in place and the other portion overlapping the top of the dust guard pocket plug to lock the latter against upward movement.
2. Dust guard plug locking means for locking the usual wood plug in the upper end of the dust guard pocket comprising a resilient metallic plate adapted to be inserted into the upper end of the pocket of a railroad car journal box so as to be disposed parallel with a side wall of the pocket, the upper end of said plate being slit to provide a number of bendable portions,

one portion being bent laterally and downwardly about the top of one side wall of the dust guard pocket to prevent downward movement of the plate during dust guard plug insertion while the other portion is adapted to be bent laterally in the opposite direction across the top of the plug to hold the latter against upward movement, the lower end of said plate being provided with a laterally disposed hook-like portion having an upstanding lip adapted to extend through the journal opening in the pocket side wall to effect holding relation with said wall and prevent upward movement of the plate.

3. Dust guard plug locking means comprising a single piece resilient member bent intermediate of its ends to provide a vertical portion and a horizontal portion, the lower end of the vertical portion terminating in a hook-like flange adapted to effect gripping relation with the wall of the journal opening in a side wall of the dust guard pocket while the horizontal portion is adapted to overlap the top of the pocket side wall and the dust guard plug, the juncture between the horizontal portion and the vertical portion being formed to yieldingly force the ends of said member in directions toward each other.

WILLIAM H. SALE.
